(57) **CLAIM**

The ornamental design for a pipe for fluid distribution, as shown and described.

DESCRIPTION

FIG. 1 is a front, top, right side perspective view of a pipe for fluid distribution, in accordance with the present invention;

FIG. 2 is a rear, bottom, left side perspective view thereof; FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines represent portions of the pipe for fluid distribution that form no part of the claimed design.
